[57] CLAIM

The ornamental design for a combined handle and lock unit, as shown and described.

DESCRIPTION

FIG. 1 is a view in perspective taken from the front and one side of a combined handle and lock unit according to our design;

FIG. 2 is a front elevational view thereof;

FIG. 3 is a rear elevational view thereof;

FIG. 4 is a bottom plan view of FIG. 2, the top plan view being a mirror image thereof;

FIG. 5 is a view taken from the right side elevational of FIG. 2; and,

FIG. 6 is a view of the opposite side thereof.

FIG. 1

FIG. 2**FIG. 3****FIG. 4**FIG. 5

FIG. 6
